UNITED STATES PATENT OFFICE.

CHARLES S. SWAIM, OF TAFT, CALIFORNIA.

SHOE-SOLE.

1,044,941.

Specification of Letters Patent. Patented Nov. 19, 1912.

Application filed May 8, 1912. Serial No. 695,955.

To all whom it may concern:

Be it known that I, CHARLES S. SWAIM, a citizen of the United States, residing at Taft, in the county of Kern and State of California, have invented certain new and useful Improvements in Shoe-Soles, of which the following is a specification, reference being had to the accompanying drawings.

10 This invention relates to improvements in shoe soles and has for its primary object to provide a pneumatic sole for house shoes or slippers, which will be very comfortable to the feet of the wearer.

15 Another object of the invention resides in the provision of a sole for shoes consisting of superposed layers of canvas and paper and having a central air-receiving cushioning member, the paper sheets rendering the 20 sole air tight so that the air will not escape through the canvas fabric.

25 A still further object of the invention is to provide a sole which may form a part of the shoe or may be manufactured in the form of an inner sole for insertion into the ordinary shoe.

30 With the above and other objects in view as will become apparent as the description proceeds, the invention consists in certain 35 constructions, combinations and arrangements of the parts that I shall hereinafter fully describe and claim.

For a full understanding of the invention reference is to be had to the following description and accompanying drawing, in which—

Figure 1 is a perspective view illustrating a shoe sole embodying the present invention, several of the layers of material being turned back to more clearly illustrate the structure; Fig. 2 is a longitudinal section; Fig. 3 is a transverse section, showing the inflating tube in its position wherewith the cushioning member is supplied with 45 air.

Corresponding and like parts are referred to in the following description and designated in the accompanying drawing, by like reference characters.

50 Referring in detail to the drawing, 5 designates a lower sheet of canvas which forms one side of an outer casing or covering and constitutes the bottom of the sole. Upon this canvas sheet a paper sheet 6 is 55 arranged and stitched at its edges thereto. The canvas sheet, however, is of greater

size than the paper sheet and extends beyond the edges of the latter for a purpose which will be fully pointed out in the following description. Upon the paper sheet 6 another layer of canvas 7 is arranged, and upon this layer of canvas the air receiving cushion 8 is disposed. This cushion consists of a sheet of canvas 9 and a sheet of paper 10, the former having secured thereto a second canvas sheet 11. This latter canvas sheet is plaited to form longitudinally extending channels 12. A sheet of canvas 13 is arranged upon the paper sheet 10, the several layers of canvas and 70 the interposed sheet of paper being securely stitched together and to the layer of canvas 7. An upper canvas layer 14 is provided between which and the canvas layer 7 the cushioning member is arranged, the canvas 75 layers 7 and 14 and the paper sheet 6 being of substantially the same dimensions. The perimetrically extending portion 15 of the larger bottom layer of canvas 5 is now provided with glue or other suitable adhesive 80 upon its upper surface and is folded over upon the edge of the canvas layer 14. The several layers of canvas 5, 7 and 14 and the paper sheet 6 are now secured together at their edges by a row of stitching indicated 85 at 16.

It will be observed that the longitudinal channels 12 of the cushion 8 are open at their ends. An inflating tube 17 is inserted between the canvas layers 9 and 11 and has 90 its inner end disposed in one of said channels. The several sheets of canvas and paper are secured together at their edges in the manner above described with the exception of the small portion through which the 95 inflating tube extends. After the cushioning member has been supplied with air by blowing through the tube and said member is inflated sufficiently, the tube is withdrawn or cut off and the opening in the side of the 100 sole closed by gluing the canvas sheets 5 and 14 together.

By providing the several superposed layers of canvas and paper and securing the edges of the sheets 5 and 14 together by 105 means of glue before stitching the same, the sole is rendered air tight so that the air cannot escape from the cushioning member through the canvas fabric.

From the foregoing description it will be 110 seen that I have devised a very simple pneumatic or air cushion sole for slippers or

shoes. The same may be either used in the nature of a separate insertible sole for ordinary shoes or the shoe may be manufactured with my improved sole forming a 5 part thereof. Owing to the simple construction of the invention it will be obvious that the same can be produced at comparatively small cost. It is also of great convenience and serviceability and provides means 10 whereby the comfort of the shoe is materially enhanced.

While I have shown and described the preferred form and construction of the invention, it will be obvious that the same is 15 susceptible of considerable modifications in the form or proportions without departing from the essential features or sacrificing any of the advantages thereof.

Having thus described the invention what 20 is claimed is:

1. A shoe sole consisting of a plurality of superposed layers of flexible material, and an air cushion interposed between said layers of material and embodying a plurality 25 of air channels, open at both ends.
2. A shoe sole consisting of a plurality of superposed layers of flexible material, and an air cushion centrally arranged between

said layers of material, said cushion comprising a plurality of longitudinal air channels extending substantially the entire length of the shoe sole and open at one of their ends.

3. A shoe sole consisting of alternately arranged superposed layers of canvas and paper, the opposite sides of the sole consisting of canvas layers, the canvas layer forming one side of the sole having its edge portion extending beyond the canvas layer which forms the other side of said sole, an air cushion interposed between the intermediate canvas and paper sheets and secured thereto, the canvas layer having the extended edge portion being adapted to be turned over upon the canvas layer forming the other side of the sole and adhesively secured thereto, stitching securing the several superposed canvas and paper layers together, and means for inflating said air cushion.

In testimony whereof I hereunto affix my signature in the presence of two witnesses.

CHARLES S. SWAIM.
